CLAIM

The ornamental design for a finger tap releasable tourniquet, as shown and described.

DESCRIPTION

FIG. 1 is a perspective view of a Finger Tap Releasable Tourniquet showing my new design with a body shown in broken lines for illustrative purposes only and forming no part of the claimed design;

FIG. 2 is an enlarged top perspective view thereof;

FIG. 3 is an enlarged bottom perspective view thereof;

FIG. 4 is an enlarged side elevational view thereof, the opposite side elevational view being a mirror image;

FIG. 5 is an enlarged end elevational view thereof;

FIG. 6 is an enlarged end elevational view thereof opposite to that shown in FIG. 5.

FIG. 4

FIG. 5

FIG. 6
